US00D789882S

(12) **United States Design Patent** (10) **Patent No.:** **US D789,882 S**
Caviaasca (45) **Date of Patent:** **** Jun. 20, 2017**

(54) **PHOTOVOLTAIC MODULE**

(71) Applicant: **STUDIO ITINERANTE ARQUITECTURA, S.L.**, Barcelona (ES)

(72) Inventor: **Antonio Caviaasca**, Barcelona (ES)

(**) Term: **15 Years**

(21) Appl. No.: **35/500,367**

(22) Filed: **Oct. 28, 2015**

(80) **Hague Agreement Data**

Int. Filing Date: **Oct. 28, 2015**

Int. Reg. No.: **DM/088462**

Int. Reg. Date: **Oct. 28, 2015**

Int. Reg. Pub. Date: **Dec. 18, 2015**

(51) **LOC (10) Cl.** **13-03**

(52) **U.S. Cl.**

USPC **D13/102**

(58) **Field of Classification Search**

USPC D13/102, 182; D28/18, 12, 17; 34/83,

34/99; 128/203.27; 60/641.14

CPC A45D 20/00; A45D 20/22; A61H 33/12;

F03G 6/064

(57) **CLAIM**

The ornamental design for a photovoltaic module, as shown and described.

DESCRIPTION

1.1 is a front view;
1.2 is a top perspective view;
1.3 is a bottom perspective view;
1.4 is a side perspective view; and
1.5 is another perspective view.
In 1.3, the broken lines are for the purpose of illustrating environment only and form no part of the claimed design.
